UNITED STATES PATENT OFFICE.

THOR MOELLER, OF BISMARCK, NORTH DAKOTA.

FIRE-ESCAPE.

1,180,409.

Specification of Letters Patent. Patented Apr. 25, 1916.

Application filed April 30, 1914. Serial No. 835,512.

To all whom it may concern:

Be it known that I, THOR MOELLER, a citizen of the United States, residing at Bismarck, in the county of Burleigh and State 5 of North Dakota, have invented a new and useful Fire-Escape, of which the following is a specification.

This invention relates to fire escapes and more particularly to one installed exteriorly 10 of a building, to be used in case of fire or allied contingencies to conduct the occupant to safety.

A further object of the invention is to provide an apparatus which is installed upon 15 the exterior of a building and includes horizontal and vertical tracks, the horizontal track extending above the windows and upon which track travels a suitable car to carry passengers from the various windows 20 to a place of safety.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without 30 departing from the spirit of the invention.

In the drawings accompanying this specification and forming a part thereof, the preferred embodiment of my invention has been illustrated, in which:—

35 Figure 1 is a view in elevation of a building equipped with my improved fire escape. Fig. 2 is a longitudinal view in section of the car. Fig. 3 is an enlarged detail view showing the electric motor and the various 40 parts adjacent thereto by means of which the various movements are imparted to the car or cage. Fig. 4 is an enlarged diagrammatic view of one of the turntables or twist- 45 ers by means of which the car passes from vertical to a horizontal track, or vice versa.

Fig. 5 is a detail view of the track and the car truck, illustrating the operating or driving mechanism. Fig. 6 is a sectional view of the track. Fig. 7 is a parallel view of 50 one of the car brake actuating mechanisms. Fig. 8 is a detail view in perspective of the engaging member of the brake actuating mechanism.

Referring to the drawings in which similar reference numerals designate analogous parts throughout the several views, 9 repre-

sents the wall of a building and which is provided with the usual windows 10, arranged in horizontal rows A, B and C, according to floors.

An upright track 11 is provided in one corner of the building and extends above the highest window and is provided with a number of turntables 12 therein which communicate with the horizontally extending tracks 13, the latter being positioned a slight distance above the windows of each floor, so that the car 35 may travel up along the vertical track 11 and across on the horizontal tracks 13 to thus reach each and every window in the building. A second vertical track 14 may be provided at the opposite corner of the wall of the building when taken with respect to the vertical track 11, especially in those cases where the building 75 is of considerable width, or the said vertical track 14 may be dispensed with and the track extend around the corner of the building and along the adjacent side. However, such changes in the location and extent of the vertical and horizontal tracks are within the scope of the present invention and will depend largely upon the contour of the building and the accessibility of the window from the interior. The track as more 80 clearly illustrated in Figs. 5 and 6, includes the spaced rack bars 15 upon both the front and rear sides of which are secured the outstanding guide plates 16 which prevent the gears 19, 20, 21 and 22 which mesh with the 85 rack bars from moving transversely of the track and also provides an engageable surface with which the brakes, later to be set forth, frictionally contact. The rear guide plates extend toward the center of the track 90 but terminate short thereof so as to define the slot 17, through which suitable electrical connection with a current carrying rail (not shown), is effected from which the car derives its energy.

The car includes a truck 18 to which are rotatably supported the gears 19, 20, 21 and 22, all of which gears mesh with the racks 15 of the rail while the forwardly and rearwardly disposed gears mesh one with the other, as 19 with 20, and 21 with 22. The shaft 23 which carries the gear 21 and the shaft 24 which carries the gear 20 extend above the truck 18 and are provided with the gears 25 secured thereto and which gears in turn mesh with a centrally disposed gear 26 from which they derive their power. The

gear 26 is rotatably carried by the hub 27 as illustrated in Fig. 3, and is driven by the electric motor 28 which has the gear 29 secured thereto and meshing with the gear 26 of the hub. The shaft 31 within the hub 27 is hollow so as to accommodate the cable 32, which cable communicates with an electric plow, not shown, which makes suitable connection with the current carrying rail before mentioned but not shown. The cable 32 extends through the hub 27 and supplies electricity to the motor controller 33 which is in convenient reach of the operator when situated upon the platform 34 especially provided for his use. The hub 27 projects through the wall 34 of the car and effects a rotating connection therewith so that the car will always be maintained in an upright position regardless of the position of the truck 20 and by which means the car is suspended from and supported by the said truck.

The body 35 of the car is preferably formed of a frame of light steel tubing 36 to which is secured a wire mesh 37, there being two layers of the latter, between which is disposed a fire-proof material 38 such as asbestos or allied substance. The door 39 opens outward, being hinged as at 40 to the lower portion of the car floor and provides a suitable bridge across which the passengers may walk to enter the car from the various windows 10. The door 39 is provided with the collapsible railing 39' for the safe entrance of passengers to the car. The car is also provided with an outlet door 41 so that when the car reaches the lowermost portion of the vertical track 11, at which point the track will extend adjacent the ground, the passengers may pass directly from the door 41 onto the ground, after which the car may return for other passengers. A suitable platform 34 is provided for the motorman or operator which is rendered accessible by a ladder 42. Positioned above the platform 34 are the windows 43 which are also of some fire-proof and transparent or semi-transparent material such as mica and through which the operator may take such observation as necessary for the proper control of the car. The windows are also movable so that access may be had to the switches which control the various turn tables, as will hereinafter be set forth at more length. Suitable brakes are provided and are rigidly secured 55 to the car truck so that the car may be quickly brought to a standstill at any position and securely locked in such position. With this in view, the brakes have been designed and include an upper plate 44 rigidly secured to the car truck and extending below the outermost plate 16 of the rail. Suitable shoulders 45 are provided contacting with the inner edges of the plates 16 and extending a short distance thereover, thus preventing the truck from rotating with respect to

the rail. Each truck is provided with a brake at its top and bottom extremity and inasmuch as the said brakes are precisely similar in construction, a detailed description of only one will be rendered.

70

A second plate 46 is secured to the truck 18 and the plates 44 and 46 are provided with the enlarged ends 48 which act as brake shoes and contact with the outer surface of the inner plate and the inner surface of the outer plate. In order to operate the shoes 48 to release the rail plates, a member 49 is provided and the member 4 is normally held with the brake shoes engaging the rail plates by the coiled spring 50, such structure providing that the brakes will be normally set holding the car rigid against movement in either direction. The member 49 which is slidably mounted and guided in its sliding movement by the said plates 44 85 and 46 is provided with the terminal hook-shaped end 51 projecting to engage or be engaged by the brake gripping member 52 as illustrated in perspective in Fig. 8.

In order that the brakes may be operated 90 from the interior of the car and furthermore to allow for the relative rotation of the truck and car, the brake actuating mechanism disclosed in Fig. 7 is provided, including a rack bar 53 from which projects the standard 54, the latter pivotally mounting a suitable brake lever 55. A hand engaging release 56 is mounted upon the handle 55 and engages one of the notches of the rack bar 53, thus locking the brake applying lever 100 55 securely in a given position. The brake applying and engaging member 52 is slidably mounted upon the rack bar 53 and is connected to the lever 55 through the intervention of the link 56.

105

From the foregoing it will be apparent that the brake applying member 52 with its terminal hooked end 57 is adapted to engage the hooked portion 51 of the wedge member 49 and forcibly retract the same, thus 110 allowing the shoes 48 of the brake plate to move out of contact with the rail side plates and allowing the car and truck to move with relation to the rail. Also the truck may be rotated with respect to the car, it being noted 115 that when such relative rotation takes place, the wedge member 49 will rotate out of contact with the brake gripping member 52, thus provided for the immediate application of the brake and preventing the movement of the truck with relation to the rail. This is of particular importance during the time the car is negotiating one of the turntables 12, as should the operator fail to apply the brake, by releasing the brake actuating lever 55 upon entering one of the turntables, the immediate application of the 120 brake will take place upon the rotation of the turntable, and the same will release the member 49 from the brake gripping mem- 125
130

ber 52. The brakes may be released from the track while the car is upon one of the vertical or horizontal tracks, four of the brake applying means as illustrated in Fig. 5 7, being provided as will be apparent by a reference to Fig. 2.

The turntables 12 are provided with the gears 58 which mesh with and are driven by the gears 59 of the motors 60. Two 10 switches 61 and 62 are provided controlling each motor and are accessible from the interior of the car so that the car traveling up one of the verticals will enter upon the turntable. The operator will then close the switch 61 which will turn the table until the track assumes a horizontal position communicating with the horizontal track. If, on the other hand, the car approaches one of the turntables from the horizontal track, 15 it may be brought into proper position with respect thereto by the switch 62. In this connection it is to be noted that suitable weights 63 are provided, by means of which the turntables will be normally held in position with the track extending vertical so that the vertical track will be continuous, thus enabling the car to travel freely up and down the vertical track without requiring a stop at each turntable in order to successfully pass therethrough. It is to be noted in this connection that the turn tables are provided with the central openings 63' so that when the car is upon the turn tables it may run beyond the center thereof and thus aid in rotating the turn tables. The enlarged openings 63' prevents the plow (not shown) from interfering with the rotation of the turn tables and further provides that it will remain in contact with the current carrying rail (not shown) during the rotation of the tables.

Although the transportant apparatus has been described and disclosed as being used as a fire escape, it will be readily appreciated that it may be used in other connections.

It is to be noted that the track may be provided with only one rack should it be so desired in which case the gears 19 and 50 22 will be replaced by suitable rollers. Such changes, however, can be made readily within the scope of the invention, as will be readily appreciated.

Having thus described my invention, 55 what I claim is:—

1. A fire escape comprising vertical and horizontal tracks, turntables at the intersections of said tracks, means for normally maintaining said turntables in such position 60 as to preserve the continuity of the vertical tracks, a car with means engaging said tracks for the moving of said car relative thereto.

2. A fire escape, comprising vertical and 65 horizontal tracks, turntables at the inter-

sections of said tracks, means for normally maintaining said turntables in such position as to preserve the continuity of the vertical tracks, a car with means engaging said tracks for moving the said car relative thereto, and brakes carried by said car adapted to engage said tracks to lock the car thereto. 73

3. In a fire escape, the combination of a vertical track, horizontal tracks communicating therewith, turntables arranged at the intersections of said vertical and horizontal tracks, a car adapted to travel along said tracks, and means for rotating said turntables, and means controlling said turntable 80 rotating means operable from the interior of said car when positioned within said turntable and upon the horizontal track adjacent thereto. 75

4. In a fire escape, the combination of a vertical track, horizontal tracks communicating therewith, turntables arranged at the intersections of said vertical and horizontal tracks, a car adapted to travel along said tracks, means for rotating said turntables, 85 means for controlling said turntable rotating means operable from the interior of said car when positioned within said turntable and upon the horizontal track adjacent thereto, and means for normally holding 90 said turntables in position to preserve the continuity of the vertical track. 95

5. A fire escape for buildings comprising a vertical track extending up one wall of the building, a plurality of horizontal 100 tracks extending above the windows and intersecting the said vertical track, switching means at the intersections of the vertical and horizontal tracks, a car engaging said tracks suspended therefrom and supported thereby, said car adapted to move in front of said windows to receive passengers therefrom, and means carried by said car for bridging the space between the car floor and the window sills. 105

6. A fire escape for buildings, comprising a vertical track extending up one wall of the building, a plurality of horizontal tracks extending above the windows and intersecting the said vertical track, switching 115 means at the intersections of the vertical and horizontal tracks, a car engaging said tracks suspended therefrom and supported thereby, said car adapted to move in front of said windows to receive passengers therefrom, means carried by said car for bridging the space between the car floor and the window sills, and means carried by the car for power operating the same. 120

7. A car for a fire escape comprising a skeleton frame, superimposed layers of wire extending therearound and a layer of fire-proof material interposed therebetween, fireproof windows in the said car, means carried by the car for bridging the space 125 130

between said car and the window of a building, and a second door provided in said car for the exit of passengers therefrom.

8. A car for fire escape apparatus comprising a body, a truck rotatably carried thereby, means carried by said body adapted to rotate the supporting wheels of said truck, means carried by said truck preventing the relative rotation of the truck and a car track.

9. A car adapted to move along vertical and horizontal single track railways, comprising a body, a car truck rotatably secured thereto, means carried by the truck preventing the relative rotation of the said truck and the car body, power means carried by the car body adapted to forcibly rotate the wheels of said car truck.

10. A car adapted to move along vertical and horizontal single track railways, comprising a body, a car truck rotatably secured thereto, means carried by the truck preventing the relative rotation of the said truck and the car body, power means carried by the car body adapted to forcibly rotate the wheels of said car truck, and a brake carried by said truck engaging the track, adapted to frictionally lock the car thereto.

11. A car adapted to move along vertical and horizontal single track railways, comprising a body, a car truck rotatably secured thereto, means carried by the truck preventing the relative rotation of the said truck and the car body, power means carried by the car body adapted to forcibly rotate the wheels of said car truck, and a brake adapted to normally frictionally engage said track to hold the car against relative movement with respect thereto.

12. A truck for single track vertical and horizontal railways comprising a plate, two pairs of gears carried thereby, the gears of each pair in mesh, a follower gear carried by one gear of each pair, and a driving gear carried by said plate, meshing with the said

follower gear for the forced rotation thereof and the forced rotation of all gears of each pair.

13. A car truck for single track horizontal and vertical railways, with the track including oppositely disposed rack bars, of a plate, two pairs of gears rotatably carried by said plate in mesh with the rack bars, and with the gears of each pair in mesh, and means for driving one gear of each pair of meshing gears.

14. A car truck for single track horizontal and vertical railways, with the track including oppositely disposed rack bars, of a plate, two pairs of gears rotatably carried by said plate in mesh with the rack bars, with the gears of each pair in mesh, means for driving one gear of each pair of meshing gears, and a brake carried by said truck engaging the rail and holding the truck in alinement therewith.

15. The combination of a rail for single track horizontal and vertical railways, comprising two oppositely spaced rack bars, overhanging side plates secured to the front and rear extremities thereof, the truck including two pairs of meshing gears, and means for driving one gear of each pair.

16. The combination of a rail for single track horizontal and vertical railways, comprising two oppositely spaced rack bars, overhanging side plates secured to the front and rear extremities thereof, the truck including two pairs of meshing gears, means for driving one gear of each pair, and a brake carried by said truck engaging the overhanging side plates of the rail and holding the truck in alinement therewith.

In testimony that I claim the foregoing as my own, I have hereto affixed my signature in the presence of two witnesses.

THOR MOELLER.
